[57] CLAIM

The ornamental design for a jewelry box, as shown and described.

DESCRIPTION

FIG. 1 is a perspective view of a jewelry box, showing my new design;

FIG. 2 is a right-side elevational view thereof, the left-side being a mirror image;

FIG. 3 is a front-end elevational view thereof;

FIG. 4 is a back-end elevational view thereof; and

FIG. 5 is a top, plan view thereof, the bottom being plane and unornamented.

*FIG. 1**FIG. 2**FIG. 3**FIG. 4**FIG. 5*
